United States Patent Office

Des. 231,867
Patented June 18, 1974

231,867

SHOULDER BAG

Matusuke Ohyama, 1-25-24 OH-Imazato,
Osaka, Japan

Filed Oct. 13, 1972, Ser. No. 297,297

Term of patent 14 years

Int. Cl. D3—01

U.S. Cl. D87—5 G

FIG.1

FIG.2

FIG.3

FIG. 4

FIG. 5

FIG. 1 is a perspective view of a shoulder bag embodying the present design;

FIG. 2 is a side elevational view thereof, showing the side of the shoulder bag which is partially concealed in the perspective view of FIG. 1;

FIG. 3 is a top plan view thereof;

FIG. 4 is an end elevational view thereof, and

FIG. 5 is a bottom plan view thereof.

I claim:

The ornamental design for a shoulder bag, as shown.
